 ark, N. J., a corporation of New Jersey

Application November 16, 1933, Serial No. 698,296

28 Claims. (Cl. 226—83)

This invention relates to machines for applying caps or the like to containers and has particular reference to machines for applying flexible hood caps over the mouths or closures of bottles containing beverages or other products commonly distributed in bottles.

It is common practice to enclose the mouth or closure of bottles containing liquids, such as milk, cream and the like, with flexible paper hoods to prevent contamination of the mouths of the bottles as the result of handling, and these hoods are applied in various ways, such as by rendering the hood plastic with heat and forming it around the mouth and neck of the bottle, by means of an adhesive, by securing the skirt of the hood around the neck of the bottle with tie means, or by employing combinations of these methods. The plastic and adhesive hood-applying methods are well known, and the tie method includes the use of separate fastening means for securing the skirt of the hood around the neck of the bottle, these tie means including wires, bands, collars, clips, staples and the like. It is with the tie method of applying hoods to bottles that the present invention is concerned, and, in particular, a method in which wire staples are employed for securing the skirt of the hood around the neck of the bottle.

In accordance with the invention, the blank for the hood is fed over the closure or mouth of the bottle, and folding fingers actuated by movement of the bottle, fold the edges of the blank against the neck of the bottle to form the skirt of the hood, which accordingly overlies the neck of the bottle and includes pleats or tabs overlapped or gathered to conform to the reduced diameter of the bottle neck. These tabs are secured in the gathered or overlapping relation by appropriately spaced wire staples driven through them and clinched against the surfaces of corresponding upwardly turned edges of alternate tabs overlying the bottle neck, the tines of the staples being directed toward each other or partially clinched before they are driven through the skirt of the hood so that they are, in effect, self-clinching and will not spread apart because of the curvature of the neck of the bottle, as would naturally result if the tines of the staples were not initially partially clinched.

In the preferred embodiment of the invention, the hood blanks provided with skirt tabs are fed in strip form to the hood-applying head and are severed from the strip by cutting mechanism synchronized with the other operations of the machine. A bottle is placed on a platform by feeding means or by hand, and the platform is raised by

a cam so that the neck thereof lies in cooperative relation with centering means mounted on the head. The centering means includes jaws which are released by a cam and momentarily encircle the neck of the bottle to properly center it with respect to the hood blank. Further elevation of the bottle causes it to clamp the hood blank between its upper end and a plunger, and substantially simultaneously a series of alternately acting double folding fingers are brought into engagement with the tabs of the blank to fold them in alternately overlapping relation into a skirt overlying the neck of the bottle and simultaneously turn up the lower edges of alternate tabs to serve as staple-clinching anvils. The overlapping tabs of the hood skirt are then simultaneously engaged by a circular series of stapling devices, which cut proper lengths of wire, form them into staple shape having inwardly turned partially clinched tines, and drive the staples through the skirt tabs with their inwardly turned tines engaging the upwardly turned edges of the corresponding tabs, which are supported by the bottle neck and accordingly act as anvils to complete the clinching of the staples between the hood tabs and their upwardly turned edges. The staples do not engage the neck of the bottle and consequently cannot tear, scratch, or otherwise mar the surface covering of the neck of the bottle, such as metal foil, or the like. Since, with the present machine, the staples are effectively and properly clinched within the hood without the use of a separate clinching anvil or the like, the skirt of the hood is tied more tightly around the neck of the bottle than is possible when a separate clinching anvil is inserted between the hood and the surface of the bottle neck, no matter how thin the anvil may be, so that the hood must be mutilated before it can be removed and tampering can be readily detected.

After the bottle has been fitted with the hood, the platform is lowered by the actuating cam to withdraw the finished bottle from the hood-applying head and the finished bottle is removed from the platform and replaced with a new one. Preferably a number of the hood-applying heads are mounted on a rotating spindle for multiple operation, bottle conveying and transferring means placing bottles on and removing them from the platforms. Safety means is associated with each head which responds to absence of a bottle on the platform to prevent operation of the hood-applying mechanism.

It will be seen that the new machine of this invention applies hoods to milk, cream, beverage,

and other bottles and containers with great speed and effectiveness and can be associated with existing high-speed container capping, filling, sealing, and other machines, without material change 5 of either machine to perform the additional step of providing the containers with sanitary hoods.

For a more complete understanding of the invention, reference may be had to the accompanying drawings, in which,

10 Figure 1 is a vertical section through the new hood- or cap-applying machine of this invention, as seen along the line 1—1 of Figure 4;

Figure 2 is an exterior view of the upper portion of the machine, shown partially in section;

15 Figures 3 and 4 are transverse sections through the hood blank feeding mechanism, as seen along the lines 3—3 and 4—4 of Figure 2;

Figure 5 is a vertical section through the hood blank feeding mechanism, as seen along the line 20 5—5 of Figure 4;

Figure 6 illustrates a development of the hood;

Figure 7 is a plan view of the bottle centering mechanism, shown partially in section, as seen along the line 7—7 of Figure 8;

25 Figure 8 is an axial section through one of the hood applying heads and illustrating the centering and blank feeding mechanisms;

Figure 9 is an axial section through the hood-applying mechanism;

30 Figure 10 is a section through the hood blank feeding mechanism, as seen along the line 10—10 of Figure 9;

Figure 11 illustrates the hood blank feed slide mechanism as seen along the line 11—11 of Figure 35 10;

Figures 12 and 13 illustrate the action of the hood folding fingers;

Figure 14 is a section through one of the folding fingers, as seen along the line 14—14 of Figure 40 13;

Figure 15 is a horizontal section through the stapling mechanism, as seen along the line 15—15 of Figure 9;

Figure 16 is an enlarged top view of one of the 45 stapling devices prior to the staple-forming operation;

Figure 17 is a similar view showing one step of the staple-forming operation;

Figure 18 is a section through the stapling device, as seen along the line 18—18 of Figure 17, and illustrates the wire-gripping action;

Figure 19 is a longitudinal section, as seen along the line 19—19 of Figure 17, and illustrates the staple-forming action;

55 Figures 20, 21, 22, 23, and 24 illustrate the various steps in the staple-forming and driving operations; and

Figure 25 illustrates a completed hood on a bottle.

60 In these drawings, numeral 30 designates the bed-plate of the machine on which is mounted the central spindle or column 31. Journaled on bushings 32 at opposite ends of the column 31 is a tubular sleeve 33 having a worm-wheel 34 65 at its lower end, which is driven by a worm 35 connected to a suitable source of power, not shown. The weight of the sleeve 33 is supported by a ring 36 secured to its upper end and resting upon a thrust bearing 37 seated on a shoulder 70 adjacent the upper end of column 31. Keyed upon the outer surface of sleeve 33 so as to rotate therewith is a carriage 38, the weight of which is supported by a collar 39 integral with sleeve 33.

75 Splined upon the upper end of sleeve 33 is

spider 40, the lower end of which is supported by a threaded collar 41, carrying the worm-wheel 42 and resting upon the ring 43, which in turn is supported by the carriage 38. The worm-wheel 42 is engaged by worm 44 so that the former, with sleeve 33, may be rotated relatively to the spider 40, so as to raise or lower it with respect to the carriage 38. The spider 40 carries a plurality of hood-applying heads 45, four being shown, each of which includes a bell 46 which carries the majority of the mechanism comprising the head 45. The spider 40, with its hood-applying heads 45, rotates with the sleeve 33 about the center column 31.

Supported upon bed-plate 30, is a cam drum 47 carrying crown cam 48 which is engaged by the rollers 49 of a plurality of slides 50, which correspond in number and position to the capping heads 45 and which are slidable in suitable guides upon the outer surface of carriage 38, so as to rotate in synchronism with the corresponding capping heads 45.

Each slide 50 carries a bottle support 51, consisting of a cup-shaped platform 52 inverted over a bearing 53 on carriage 50 and slidably mounting the plunger 54 on platform 52, which is normally supported by the coil spring 55 encircling centering rod 56. The upper surface of bottle support 51 is provided with a cushion 57, which, together with spring 55, provides a non-rigid support for the bottle B to which a hood is to be applied. The bottle B is illustrated as a beverage bottle provided with a wrapper with which the hood cooperates to form a completely closed package, but it is to be understood that the bottle may be unwrapped, such as a milk bottle or the like.

Mounted adjacent the first station of the hood-applying machine of this invention is a bottle transfer mechanism 58, which transfers bottles 40 to be hooded from a conveyor 59, or the like, receiving the discharge from a capping, filling, corking, or like, machine. The bottle transfer mechanism 58 includes a spindle 59 journaled on bed-plate 30 and carrying a worm-wheel 60 which is driven by a worm 61 connected to a suitable source of power. The upper end of spindle 59 carries a series of sets of bottle-gripping fingers 62 of conventional design, which are actuated by the cam 63 carried by the upper end of the housing 64 of the spindle 59, and arranged to actuate the bottle-gripping fingers 62 in such a way that bottles are removed one at a time from conveyor 59 and transferred to one of the bottle supports 51 of the capping machine of this invention, the transfer mechanism 58 moving in synchronism with the corresponding hood-applying head 45.

Cooperating with the bottle-gripping fingers 62 of the transfer mechanism 58, is a plurality of sets of bottle-gripping fingers 65 which are carried by the ring 43 rotating with sleeve 33. The leading pairs of bottle-gripping fingers 65 of each set are secured on a pin 66 journaled on a bracket 67 on ring 43 and carrying at its lower end a crank 68 which engages the crank 69 on the upper end of a pin 70 which is journaled in carriage 38. The lower end of pin 70 is provided with a crank 71 carrying a roller 72, which follows the contour of a stationary cam 73 mounted on the upper surface of cam drum 47.

The contour of cam 73 is such that as one of the bottles B is placed upon the bottle holder 51 by transfer fingers 62 of transfer mechanism 58, it is embraced by the bottle-holding finger 65, the 75

leading pair of which is moved into engagement with the leading surface of the bottle B, whereby the latter is positioned between these fingers and the stationary pair of fingers 65 in accordance with the movement imparted to the leading fingers 65 by cam 73. Each bottle B received by the capping machine is firmly held against lateral displacement on the bottle support 51 by the fingers 65 while it is carried through the machine, the cam 73 again actuating the fingers 65 to release the bottle B after the hood has been applied thereto.

The contour of crown cam 48 is such that immediately after a bottle B is received by bottle support 51, the corresponding slide 50 is raised so that the bottle B is brought into position for cooperative relationship with the corresponding capping head 45, in the manner illustrated in Figure 8. At approximately the same time, a stationary cam 75, mounted on a gear 76 carried by the upper end of column 31, actuates a lever 77 mounted on the upper end of a pin 78, journaled in spider 40, as shown especially in Figure 2. The lower end of pin 78 carries a lever 79, which normally holds pawl 80 in the dotted position indicated in Figure 7. Pawl 80 is connected to a centering mechanism supported by bell 46, which includes a stationary ring 81 slidably mounting the ring gear 82, which carries the pawl 80 and is urged in a clockwise direction, as seen in Figure 7, by the plunger 83 engaging an abutment 84 thereon under the influence of a spring 85 seated within a recess in stationary ring 81. Pivoted at equally spaced points on ring 81 are three centering fingers 86, the inner ends of which are provided with pads 87 shaped to the contour of the neck of the bottle adjacent the bead D thereof, as is illustrated in Figure 8. The outer ends of centering fingers 86 are provided with gear segments 88 which mesh with the teeth of ring gear 82.

As the bottle B is elevated to the position illustrated in Figure 8, cam 75 releases lever 79 so that the spring 85 urges the pads 87 of centering fingers 86 into engagement with the neck of bottle B so as to resiliently embrace the latter to center the bottle with respect to the plunger 74 of the head 45. The action of this centering mechanism is illustrated in Figures 7 and 8, and is only momentary, the cam 75 immediately returning lever 79 to the dotted position illustrated in Figure 7, whereby it reengages the pawl 80 to rotate gear 82 in a counter-clockwise direction and withdraw centering fingers 86 from engagement with the neck of the bottle B to the normal disengaged position, illustrated by the dotted lines in Figure 7, so that the bottle B may be elevated further.

Overlying the upper end or cap C of bottle B, as it is being centered by the centering mechanism just described is a hood blank E which is illustrated in Figure 6. This hood blank E preferably comprises four broad, long tabs 89, the lower edges 90 of which are scored for folding inwardly against the inner surface of the tab 89. Interposed between the broad tabs 89 are short and narrow tabs 91 which are connected to the broad tabs 89 by gussets 92, while the octagonal center 93 of the cap E, defined by scored creases, is of a size corresponding substantially to the mouth or crown cap C of the bottle B. Preferably one of the tabs 89 is provided with a finger piece 94 and tearing lines 94', whereby the hood may be torn from the bottle. The hood blanks E are connected together in a strip 95 which is fed intermittently downwardly from an overhead reel feed-

ing mechanism 97 through guides 96 to guides 96' where they are advanced to properly centered position with respect to the mouth, cap, or upper end of the bottle B by feed mechanism acting in synchronism with the overhead feed mechanism. 5 These mechanisms operate after each hood-applying operation to supply a hood blank E to the capping head 45 for application to the next succeeding bottle, the cap being also severed from the strip by suitable mechanism to be described along 10 with the hood blank feeding mechanisms. Suffice to say for the time being that a hood blank E lies in the guides 96' in readiness for cooperating with a bottle being elevated against its lower surface.

Normally splined in mesh with gear 107 and 15 journaled on spider 40 so as to roll around the gear 76, as the spider rotates, are four pinions 108 arranged to be clutched to and declutched from gear 76 for placing the mechanism of the corresponding capping head 45 into and out of 20 operation. This pinion 108 is normally held in raised position by coil spring 108' encircling its sliding shaft 120, and illustrated in Figure 9. As cam 48 continues to raise bottle B, with the severed hood blank E clamped between the bottle top or 25 cap C and the rod 74, the latter actuates lever 119 pivoted on spider 40 and connected intermediate its ends to pinion 108, as is illustrated in Figures 1 and 9. This pinion is slidable on jack shaft 120 and is moved downwardly by the action of rod 74 30 into engagement with gear 76 to drive gear 107; at the same time roller 119' is raised from the notch 123 of cam 122. Cam 122 holds lever 119 in the elevated position until gear 107 makes a complete cycle, after which the roller 119' drops 35 into the notch, disengaging pinion 108 from gear 76 and locking gear 107 until rod 74 is actuated by the next bottle. The clutching action and consequent operation of the capping head 45 are delayed until the proper time by cam 122, which is when 40 the bottle has been elevated by cam 48 to a position near the end of its stroke.

The inner end of lever 119 is extended and carries a roller 109' cooperating with stationary cam 109 mounted on gear 76, as is illustrated in 45 Figures 1 and 4. This cam is opposite the notch 123 in cam 122 and insures that, after completion of each operation of the capping head, roller 119' drops into the notch 123 of cam 122 to disengage gear 108 from gear 107. Accordingly, if 50 spring 108' should fail at any time, due to breakage or the like, cam 109 will disengage gear 108 at the proper time to prevent the capping head 45 from continuing to operate out of synchronism with the movement of the bottles with the liability of breakage of bottles or mechanism. Also, if no bottle is in position on bottle support 51, rod 74 will not be elevated and the pinion 108 will remain declutched from gear 76 and the hood-applying mechanism will not be operated. 55

In addition to actuating clutch driving gear 108, the elevation of rod 74 by bottle B also causes movement of lever 143 about its pivot 144 to engage roller 145 at its free end with stationary cam 146, the operating contour of which is similar to 60 the contour of crown cam 48 so that the bottle B is securely clamped between the disc 147 on the lower end of rod 74 and the bottle support 51, as it moves up and down in response to actuation jointly by cams 48 and 146. 70

Located within a recess in rotating sleeve 124, but stationary with respect thereto, is an inverted cup-shaped frame 148 on which is telescoped the reciprocating tube 149, as is shown especially in Figure 9. Slidable on rod 74 within frame 148 75

is a collar 158 resiliently urged toward disc 147 by means of compression coil spring 150. The upper end of tube 149 is threaded to a second tube 151 separated from the interior of rotating sleeve 124 by the bushing 152 and carries at its upper end a collar 153 to which is connected one end of a lever 154 pivoted at 155 on spider 40 and having a roller 156 at its free end which follows the contour of a stationary cam 157 as the spider rotates. The cam 157 controls the axial position of tube 149.

Seated in the groove of collar 158 of tube 149 are the ends of several bell crank levers, alternate ones of which are longer than the remaining levers. Long bell crank levers 159, of which there are four in number, are adapted to cooperate with long tabs 89 of the hood blank illustrated in Figure 6; whereas the short bell crank levers 160 are adapted to cooperate with the short tabs 91 of the hood blank, as is illustrated in Figures 12 and 13. These bell crank levers are pivoted on frame 148, as is illustrated in Figures 9, 12, and 13.

The short bell crank levers 160 are fitted with side flanges 161 between which is a swinging block 162 pivoted on the lever 160 and urged inwardly about its pivot by a spring 163 engaging a plate 163' secured to the rear surface of block 162, as is illustrated in Figures 13 and 14. The spacing between the flanges 161 is slightly greater than the width of the corresponding short tab 91 of the hood blank E, so that the latter is embraced thereby and prevented from being laid askew on the bottle neck as the block 162 presses it down upon the bottle neck.

Each long bell crank lever 159 is provided with a resilient folding finger 164, the tip of which is curved rearwardly so that the finger will smoothly apply the corresponding long tab 89. Associated with each folding finger 164 is a hook finger 165 pivoted on a downward extension 148' of frame 148 and having a rearwardly extending lug 166 which is engaged in a notch 167 in the lower end of a pin 168 slideable in frame 148 and carried by tube 149 so as to reciprocate therewith. The hook finger 165 is provided with two hooks forming the slot 169 which is adapted to receive and upwardly and inwardly turn the edge 90 of the long tab 89 of the hood blank E.

As the bottle B rises further with the severed hood blank E clamped between its upper end or cap C and the disc 147 of rod 74, as is illustrated in Figure 8, the collar 158 is raised thereby to swing the folding fingers 162 and 164 toward the neck of the bottle B to fold the corresponding tabs downwardly upon the neck of the bottle to form the skirt of the hood, the longer folding fingers 164 engaging the corresponding long tabs 89 first to fold them down, while the shorter folding fingers 162 subsequently engage the short tabs 91 to fold them on top of the under-folded portions of the long tabs 89 with the flanges 161 laying them straight.

Immediately prior to the inward movement of corresponding long finger 164, cam 157, by means of lever 154, lowers tube 149—151 and pins 168 to move the corresponding hook fingers 165 inwardly to engage the lower edge 90 of each corresponding long tab 89 with its slot 169 and fold it inwardly and upwardly, as indicated in Figure 12. Subsequent retraction of pin 168 by cam 157 causes reverse movement of corresponding hook finger 165, so that the latter is with-

drawn from corresponding long tab 89, in the manner indicated in Figure 13, while long finger 164, continuing to descend, creases the upwardly turned edge 90 of corresponding long tab 89 against the outer surface of the bottle B. Short fingers 162 follow the movements of long fingers 164 and fold the short tabs 91 downwardly to overlap the edges of the adjacent long tabs 89, as is indicated in Figure 13.

After the hood skirt has been formed around the neck of the bottle by the interfolding of the tabs of the hood blank E, in the manner described, the fingers continue to hold the skirt tightly around the neck of the bottle while the stapling operation takes place.

Four stapling devices are provided for each hood-applying head 45, and one of these stapling devices corresponds to each of the four short tabs 91 of the hood blank E. These stapling devices are indicated at 170 in Figures 1, 8, 9, 10, 15, and are illustrated in detail in Figures 16, 17, 18, and 19. Each stapling device includes a block or base 171, secured to the bell 46 of the corresponding hood-applying head 45. Journaled in the block 171 and extending upwardly therefrom is a shaft 172 fitted with a pinion 173 which meshes with one of the four mutilated gears 125, 126, 127 or 128 keyed to the lower end of revolving sleeve 124, as is illustrated in Figure 9. For example, the pinion 173 of the right-hand stapling device 170, illustrated in Figure 9, meshes with lower mutilated gear 125, while the pinion 173' of the left-hand stapling device 170, meshes with mutilated gear 127, and the pinions of the other two stapling devices, not shown in Figure 9 but illustrated in Figure 15, mesh with mutilated gears 126 and 128, respectively.

Mutilated gears 125 to 128, inclusive, are provided with toothed segments of approximately 40 90° and the segments of the several gears are spaced 90° apart, so that the four stapling devices 170 are operated simultaneously, despite the fact that they are spaced 90° apart, as indicated in Figure 15. The construction of the four stapling devices is identical, as is their operation, and consequently a description of the operation and construction of one of them will suffice.

Referring to Figure 16 of the drawings, the lower end of shaft 172 is fitted with a pinion 174 which meshes with a Geneva gear 175 journaled on block or base 171, and carrying friction roller 176, as shown especially in Figure 17. Pivoted at 177 on block or base 171 is a lever 178 on which is journaled a friction roller 179 cooperating with friction roller 176, as shown in Figure 17. Roller 179 is normally urged into contact with roller 176 by a spring 180 interposed between lever 178 and base 171, as shown in Figure 17. The end of the lever 178 adjacent its pivot 177 is provided with a horn 181 adapted to be engaged by a cam 182 fixed on shaft 172 so that as the latter rotates, cam 182 periodically engages horn 181 to disengage friction roller 179 from driven friction roller 176 to stop the intermittent feed of the staple wire from reel 183 through thimble 184 into guide tube 186 which leads to a second thimble 187 at the front end of the stapling device, as shown in Figure 17. Thimble 187 leads into an 70 elongated slot 188 formed in stapling device block or base 171, and the intermittent feed provided by the Geneva gear-driven feed rollers 176 and 179 causes periodic advance of the end of the wire into engagement with the far wall of 75

slot 188, which, accordingly, acts as a measuring gauge for determining the length of the wire to be severed to form the staple. The rollers 176 and 179 overadvance the wire slightly so as to spring it slightly to insure that it will be the right length and not short.

Slidably mounted within slot 188 is the cutter and forming slide 189, the lateral edge of which, as seen in Figure 18, carries a blade 189' 10 to sever the wire extending across the slot 188. Slidably in a slot in the slide 189 is the staple driver 190, having grooves of substantially semi-circular section in its lateral sides cooperating with corresponding grooves on the inner walls of 15 the slide 189. Slide 189 is connected by link 191 to a crank pin 192 in shaft 172, while driver 190 is connected by link 193 to crank pin 192 so that slide 189 initially advances beyond driver 190 but is retracted while driver 190 still advances.

Pivoted at one end on the base 171 with its other end urged into slot 188 by spring 194 is initial forming arbor 195 with which the grooved end of driver 190 cooperates to hold the center 25 of the severed wire length while slide 189 bends the ends thereof forwardly around the sides of arbor 195 to form a staple of U-shape, the tines of which lie in the grooves in the inner walls of the slide 189, as is illustrated in Figure 20. The 30 end of arbor 195 is lifted out of slot 188 by engagement of its lower sloping surface by the nose of the advancing driver 190, which then holds the rear end of and advances the staple further along the grooves in the inner walls of slide 189 35 into the bending jaws 196, in the grooves of which the tines of the staple are flared outwardly, as shown in Figure 21.

Extending upwardly between the jaws 196 is the nose 197 of a final-forming, spring-pressed 40 arbor 198, which is pivoted at 199 in the block 171 for downward swinging movement. The nose of the arbor 197 conforms to the outwardly flaring grooves of the jaws 196 and the tines of the staples are driven between these jaws 196 and 45 the nose of arbor 197 so that they are spread apart and the tips thereof are simultaneously curved toward each other. The cam-action of the advancing driver forces the arbor 197 from between the jaws 196 and the freed staple is advanced by driver 190 between the narrower tips 50 of jaws 196, which accordingly again bend the tines of the staple into substantially parallel relation with their tips curved toward each other in partially clinched condition before being presented to the hood, as is illustrated in Figure 55 22 at S.

As the slide 189 advances, a spring 200 carried thereby is pressed against a pawl 201, projecting into the wire thimble 187 (Fig. 18) to 60 cause it to clamp the unsevered length of wire during the severing operation in order to prevent it from springing back because of its natural resiliency. Accordingly, the wire will not be short when next advanced by the feed rolls 65 176, 179, as would be the case if the wire had retracted. Because of this wire-gauging arrangement, the tines of the staple, instead of being of different lengths, are of the same length and the staple can be driven evenly and accurately in consequence.

The jaws 196 are also slidably mounted in the block or base 171 of the stapling device, and as the slide 189 advances, lateral extensions 202 thereof engage the rear ends of the jaws 196 and 70 project them into engagement with the lower end

of corresponding hood blank tab 91, immediately beneath the end of corresponding short folding finger 162, which is made short for the purpose of providing the necessary clearance for the stapling device jaws 196, as is illustrated in Figures 1 and 13. As is indicated in Figure 15, the long folding fingers 164 lie between the stapling device 170 and do not interfere with their operation but continue to hold down long tabs 89 during the stapling step. The four jaws 196 of the 10 corresponding four stapling devices simultaneously engage the corresponding hood tabs 91 so as to substantially encircle the neck of the bottle B in the manner illustrated in Figure 15, whereby the skirt of the hood is moulded into close 15 conformance with the neck of the bottle before the partially clinched staples are driven through the hood to tie it securely in this condition.

The partially clinched pre-formed staple S is presented to the skirt of the hood for the stapling 20 operation by the forwardly projected jaws 196 of the stapling device 170, the tips of the staple tines engaging the outer surface of the corresponding downwardly folded narrow tab 91 at the relatively sharp angle indicated in Figure 25 23. Immediately below the narrow tab 91 are the abutting edges of the adjacent long tabs 89, the lower edges 90 of which are folded upwardly and lie immediately below upon the surface of 30 the bottle B.

From the position indicated in Figure 22, staple driver 190 drives staple S through the relatively non-rigid layers 91 and 89 of the hood skirt without deflecting the tines in any way, as is illustrated in Figure 23, until the inwardly turned tips of the staple tines engage the upturned tab edges 90, which, because they are rendered firm by being immediately backed by the rigid surface of the bottle B, act as anvils and deflect the tips of the tines inwardly toward each other. This inward deflection of the tines is induced by the curvature of the tips thereof produced jointly by arbor 197 and jaws 196, these tips sliding on but not penetrating the surfaces of the corresponding tab edges 90 as they engage 40 the firm smooth surfaces thereof.

Further movement of the driver 190 causes the tines of the staple to clinch completely to the position indicated in Figure 24, the edges of the tabs 89 being drawn toward each other by the 50 movement of the staple tines so that the skirt of the hood tightly embraces the neck of the bottle B in the manner illustrated in Figure 25, and cannot be withdrawn over the flaring head D without mutilation, so that any tampering 55 with the hood can be readily detected. Accordingly, with the hood applied by the machine of this invention, a tamper-proof package is produced. Displacement of the hood may be readily accomplished by tearing it by lifting the finger-piece 94 shown in Figure 6.

The simultaneous driving of the four staples S which tie the hood to the bottle is not accompanied by impact but can be described more accurately as being a pressing action, the tines of the four staples penetrating the skirt of the hood simultaneously and then being deflected by engagement with the upturned tab edges 90 in the manner described, so that no cracking or other injury of the bottle neck can take place nor is 70 the surface of the hood skirt mutilated or marred by engagement between it and the stapling device jaws 196. Furthermore, in order to accommodate bottles having oversized necks without breaking them or the stapling devices, the link 75

193, which actuates staple driver 190 is made 5 resilient by a saw cut 193', so that if the driver 190 engages an oversized bottle neck, the link 193 will shorten automatically to compensate for the oversize, returning to normal length immediately after the staple-driving operation because of its natural resiliency.

Also, because the tines of the staple are finally clinched behind the upturned edges 90 of the hood, they cannot engage and thus mar, scratch, or tear the bottle wrapper or the metal foil or paper covering of the neck of the bottle, although if desired, the wrapper of the bottle may be directly stapled to the hood by omitting the 15 upturned edges 90 of the hood, in which case the tines of the staple will penetrate the softer paper wrapper and finally clinch against the surface of the bottle neck.

After the stapling operation is completed, cam 20 48 again lowers the hooded bottle B from out of the capping head and transfer mechanism, not shown but similar to transfer mechanism 58, removes the completely hooded bottles from their supports 51 and transfers them to a conveyor or 25 the like, not shown.

As the hooded bottle is withdrawn from the capping head 45, the paper strip 95 is advanced to provide the head with a new hood blank E in readiness for the next hood-applying operation, and this mechanism will now be described. 30 As was previously mentioned, the hood blank strip 95 is fed downwardly through guide 96 by an overhead intermittent feed mechanism to a second intermittent feed mechanism which operates in synchronism therewith. The overhead feed mechanism includes four driven reels 97, drawing the hood blank strips 95 from the supply rolls 110, mounted concentric with the axis of rotation of the machine and housed in magazine 98 mounted on the top 99 of the machine.

Each reel 97 is carried by a removable spindle 100 splined in the upper end of an intermittent moving shaft 101, as is illustrated in Figures 4 and 5. Shaft 101 is journaled in the rotating spider 40 and carries at its lower end a ratchet wheel 102 which is engaged by pawl 103 mounted on one end of double lever 104 journaled on the lower end of shaft 101, as is illustrated in Figures 4 and 5. The other end of double lever 45 104 carries a cam-following roller 105 which engages the edge of a disc cam 106 mounted on the upper surface of a gear 107 driven by pinion 108 in the manner described, so that pawl 103 advances reel 97 a sufficient amount to feed the strip 95 the length of one hood blank E through guide 96 toward the corresponding capping head 45 for each revolution of spider 40. Since there are four capping heads 45, four hood blanks are fed toward the corresponding capping heads during each complete revolution of spider 40.

The magazine 98 contains four rolls 110 of hood blank strips 95, one of which leads to each of the four reels 97 over an idler pulley 111, as is illustrated in Figure 3. The idler pulley 111 is carried by levers 112 pivoted on the shaft of reel 97 and urged in a counter-clockwise direction, as seen in Figure 3, by spring 113, interposed between one of the levers 112 and the magazine 98, so as to take up slack in the strip 95. In order to hold the hood blank strip 95 on the reel 97, an arcuate guide 115 partially encircles the reel 97 and is carried by the lever 116 pivoted at 70 117 on the top plate 99 and adjustable about its pivot 117 by a set screw 118, engaging the magazine 98. The reel 97 is provided with spaced sets

of teeth 97' which are of such size, shape and location as to lodge behind the projecting lateral tabs 91 of the hood blank strip 95 and thus positively feed the latter step-by-step as the reel 97 rotates step-by-step in the manner described. 5

In addition to the mutilated gears 125, 126, 127, and 128, sleeve 124 carries gear 129 and crown cam 130. Gear 129 meshes with and drives a pinion 130' journaled on the bell 46, as illustrated in Figure 10. Pinion 130' is mounted on a shaft 10 131 journaled in the bell 46 and carrying at its lower end a crank pin 132 fitted with a cross-head 133, slideable in a corresponding slot in lever 134 pivoted at one end on the bell at 135 and connected at its free end to the paper feed 15 slide 136, as is shown especially in Figures 10 and 11.

Paper feed slide 136 carries pivoted feed fingers 137 which engage the hood blank strip 95 behind the laterally projecting tabs 91, illustrated 20 in Figure 6, so that when the slide 136 is reciprocated by the crank pin 132, as is permitted by the sliding connection between lever 134 and slide 136 (Fig. 10) in a manner readily understood, the hood blank strip 95 is advanced one 25 hood blank length in guides 96' into the center of the head 45 in position for cooperation with the next bottle to be fitted with the hood. The feed fingers 137, after advancing hood blank strip 95, lodge behind the rearward edges of the 30 lateral tabs 91, so as to prevent the hood blank strip from springing backwardly as a result of its natural resiliency, so that the hood blank is not only advanced to proper position by the fingers 137, but is also held in that position by the 35 fingers 137. A knurled handle 137' is connected to the first of the feed fingers 137 whereby they may be lifted to release the hood blank strip 95 for adjustment. The movement of the feed slide 136 is synchronized with the step-by-step movement of the corresponding hood blank strip reel 97, although a slack is left in the hood blank strip 95 amounting to one or two hood blanks E in length to prevent tearing of the strip in the event that there are any irregularities in cutting 40 of the strip 95. 45

As each leading hood blank E is advanced into position for alignment with the top or cap C of the next bottle which is to be provided with a hood, it is automatically severed from the hood blank strip 95 by a moving cutter blade 138, carried by the bell 46 and cooperating with the stationary cutter blade 139 (Figs. 8, 9, and 10). Moving cutter blade 138 is actuated by a rod 140 having a roller 141 at its upper end which follows the contour of revolving cutter cam 130, which is so arranged that, as the leading hood blank of the hood blank strip 95 is advanced and held in proper position with respect to the bottle B by the feed fingers 137, it raises moving cutter blade 138 to sever the hood blank from the hood blank strip 95, the movement of the cutter being synchronized with the movement of the hood blank strip 95. A spring-pressed plunger 142 carried by moving blade 138 clamps the hood blank strip against the upper blade 139, while the blank is being severed therefrom. The cutting of the hood blank E which is retained in the guides 96' is the last operation of the stapling head 45 after the stapling operation and places 70 the head in readiness for the next stapling operation. 75

Although the operation of the machine of this invention will be readily understood from the foregoing description, it will be reviewed. Bottles

B, either wrapped or unwrapped, are transferred one at a time by the transfer mechanism 58 from a conveyor 59 or other machine to the bottle supports 51 of the hood-applying machine, as is illustrated graphically in Figure 1. The hood-applying mechanism rotates continuously in one direction about its center column 31, and as it rotates the bottle supports 51 are elevated and lowered by stationary cam 48 which the follower 10 rollers 49 of the bottle supports 51 follow.

The bottles B, held securely on the corresponding bottle supports 51 by fingers 65, are accordingly first elevated by cam 48 into engagement with a severed hood blank E underlying the clamping disc 147 on the lower end of rod 74 in the guides 96. When the bottle B reaches this elevated position it is momentarily held stationary by cam 48, while it is centered with respect to the hood-applying head 45 by centering mechanism illustrated in Figures 7 and 8, which is operated by lever 79 actuated by stationary cam 75 around which the cam follower 77 rolls as the hood-applying head 45 rotates. Actuation of the centering mechanism lever 79 results in the momentary release thereby of spring 85 which urges the centering fingers 86 resiliently around the neck of the bottle B, to center the same in the manner indicated in Figures 7 and 8, whereupon cam 75 again actuates lever 79 to withdraw centering fingers 86 for further elevation of the bottle B.

Further elevation of bottle B with the hood blank E clamped between its mouth, top or cap C and clamping disc 147 elevates rod 74 to swing the end of lever 143 into engagement with cam 146, the contour of which is like that of cam 48, so that as the capping head 45 rotates the bottle is held securely upon its support 51. This support 51 is not rigid but will recede in the event that a taller bottle than usual is placed thereon, so that there is no danger that the bottle will be broken by being clamped between inflexible supports.

Although the centering device operates in any event, the remainder of the hood-applying mechanism of head 45, including the hood-blank feed, hood-blank severing and stapling mechanisms, does not operate if a bottle is not in position on the corresponding bottle support 51, the presence of a bottle being necessary to initiate operation of these mechanisms. Thus, the elevation of the bottle B beyond the place where it picks up the hood blank E, effects the engagement of pinion 108 with gear 107 at a time determined by delayed-action cam 122, which time is after the first hood blank E has been folded around the neck of the bottle, prior to the stapling operation controlled by pinion 108.

The steps of the hood folding operations are illustrated graphically in Figures 8, 12, and 13, and are jointly effected by the movement of the bottle and by cam 151, the latter controlling the folding under of the ends 90 of the long tabs 89 by means of hook fingers 165. As indicated in Figure 8, the depending folding fingers 162 and 164, in their original position, fold down the respective short tabs 91 and the long tabs 89 toward the neck of the bottle, the action of the fingers 164 preceding because they are longer, so that the long tabs 89 are folded down first with the edges of the intermediate short tabs overlapping and being guided straight by the flanges 161 in the manner illustrated in Figure 14.

However, before these fingers are moved by

further elevation of the bottle, the hook fingers 165 are actuated by cam 157 to move inwardly from the position shown in solid line in Figure 8 to the dotted line position to engage the lower edges of the long tabs 89 in the hook finger slots 169 and fold the edges 90 upwardly as seen in Figure 12. Immediately thereafter, as the hook fingers 165 are being withdrawn by cam 151, bottle B raises rod 74 so that disc 147 engages and elevates collar 158 to cause the latter to swing the bell cranks 159 and 160 about their stationary pivots to move the respective long and short fingers inwardly so that they press the corresponding long and short tabs 89 and 91 against the bottle neck with a resilient pressure provided by the natural resiliency of long fingers 164 and by springs 163 of short fingers 162. This arrangement also automatically compensates for variations in size of the bottle necks. Further elevation of the bottle causes the folding fingers 20 to smooth the corresponding tabs into a skirt closely encircling the neck of the bottle, the long fingers 164 creasing the upwardly turned edges 90 of the long tabs 89 against the bottle neck in the manner illustrated in Figure 13, which also 25 shows the hood in position for stapling.

The pinion 108, being normally in splined engagement with stationary gear 76, rolls around the latter as spider 40 rotates and accordingly drives corresponding gear 107, the four pinions 30 108 coming into action successively in a manner readily understood. This rotation of gear 107 effects rotation of mutilated gears 125, 126, 127 and 128, which initiates the simultaneous operation of the corresponding four stapling devices 35 illustrated in Figure 15. Each of these devices feeds wire stock from reel 183 through tube 186 across slot 188, which acts as a gauge, while clamp 201 holds the wire as it is cut off by and bent into U-shape around anvil 195 by slide 189, 40 as is illustrated in Figure 20. The anvil 195 is then forced out of the way by driver 190, which advances the staple blank into grooves formed jointly by jaws 196 and arbor 197 so that the tines are spread apart although the tips of the 45 tines thereof are bent toward each other in the manner illustrated in Figure 21. Arbor 197 is then forced downwardly out of the way by the cam surface of driver 190, as is indicated in Figure 19, and the driver 190 advances the staple 50 blank between the confining jaws 196 which bend the tines of the staple blank back into parallel relation, with the tips thereof being bent toward each other in partially clinched form, as is illustrated in Figure 22.

During the last stage of the staple-forming operation, the jaws 196 are projected forwardly so that they engage the short tabs 91 of the hood skirt, the four jaws closely encircling the neck of the bottle to press the skirt tightly around it. 60 The folding fingers 162 which hold the short tabs 91 down are made short to accommodate the stapling jaws 196 beneath them, while the long folding fingers 164 lie between adjacent stapling devices as is illustrated in Figure 15.

Although the jaws 196 of the stapling device are positively projected forwardly firmly against the bottle necks, they are not rigid, but are allowed a sufficient degree of resiliency to accommodate oversize bottle necks without breakage. 70 This resiliency is provided by the slot 193 shown in the jaw-advancing link 193 in Figure 17.

The preformed partially clinched staple S is presented to the lower end of the short tab 91 which overlaps the upwardly turned edges 90 of 75

the underlying long tabs 89, the relation of the several tabs, staple, and stapling mechanism before driving being illustrated in Figure 22. As was previously explained the partially clinched tines of the staple S are forced through the relatively non-rigid short tab 91 and abutting underlying edges of the adjacent long tabs 89 until they engage the firm upturned edges 90, which, backed by the bottle neck, act as anvils to turn 5 the partially clinched tips of the tines toward each other to complete the stapling operation, as is illustrated in Figures 23 and 24, the staple tines being flattened between the long tabs 89 and their upwardly turned edges 90 in the manner illustrated in Figures 24 and 25.

It will be observed from Figure 23 that the tips of the staple tines lie within the angle defined by the radial lines drawn from the center of curvature of the bottle neck to the ends of the cross-bar, head, or widest part of the staple S, i. e., the tips of the staple tines converge at an angle greater than the radial angle of curvature of the neck of the bottle as determined by the head or widest part of the staple, so that they are not deflected outwardly because of the curvature of the neck of the bottle, but turn inwardly because of their partially clinched condition. Thus, each staple is perfect in formation, which is not the case with staples having their tines at right angles 20 to the head or at an angle greater than normal, i. e., so that they lie outside of the radial lines connecting the center of curvature of the bottle neck and the ends of the head of the staple, or with their tips outside of these radial lines, for 25 the tines of such staples spread and are likely to be deflected in any direction because of the curvature of the neck of the bottle.

After completion of the stapling operation, the jaws 196 are withdrawn and cam 48 lowers the 40 hooded top of the bottle out of head 45 and it is transferred from the bottle support to a conveyor or the like by a transfer mechanism similar to mechanism 58 and cooperating with cam 73 which opens the gripping fingers 65 at the proper time 45 to release the bottle for transfer by the gripping fingers of the transfer mechanism.

As the bottle is withdrawn from the capping head 45 the hood blank feeding and severing mechanism comes into action, being driven by 50 pinion 108 in synchronism with the overhead hood-blank feeding mechanism, and advancing the hood blank strip 96 with slide 136 and fingers 137 to place a hood blank E in guide 96' in position for engagement by the mouth or cap C of the 55 next bottle to be hooded. After the leading hood blank E is positioned, the cutter cam 130 comes into action to raise blade 138 into cooperation with blade 139 and sever the blank from the strip 95. This is the last step of the operation of the hood- 60 applying mechanism, and is followed by the action of cams 122 and 109 in lowering the inner end of lever 119 and raising the opposite end thereof to cooperate with spring 108' in elevating pinion 108 to declutch it from gear 76.

65 It will be seen that the new machine of this invention embodies many improvements which provide the important advantages of high speed operation, accuracy, safety, and uniformity, and while a preferred embodiment of the invention has been illustrated and described herein, it is to be understood that the invention is not limited thereby but is susceptible of changes in form and detail within its scope.

We claim:

1. In a machine for applying a skirted hood to

a bottle, the combination of a support for the bottle, means for folding the hood over the mouth of the bottle, the skirt of the hood so folded including a plurality of layers of hood material, means for holding a partially-clinched staple adjacent the hood skirt, and means for driving said staple through said layers of hood material for final self-clinching against the underlying bottle.

2. In a machine for applying a skirted hood to a bottle, the combination of a support for the bottle, means for folding the hood over the mouth of the bottle and mechanism for driving a staple through the skirt of the hood to secure it around the neck of the bottle, said mechanism comprising means for preshaping a staple with the tines converging, and then driving the staple in that shape through the skirt of the hood for self-clinching against the bottle as an anvil.

3. In a machine for applying a skirted hood to a bottle, the combination of a support for the bottle, means for folding the hood over the mouth of the bottle and mechanism for driving a staple through the skirt of the hood to secure it around the neck of the bottle, said mechanism comprising means for preshaping a staple with the ends of the tines converging to an angle greater than the radial angle of the curvature of the neck of the bottle, as determined by the widest part of the staple, and then driving the staple in that shape through the skirt of the hood for self-clinching against the bottle as an anvil.

4. In a machine for applying a skirted hood to a bottle, the combination of a support for the bottle, means for folding the hood over the mouth of the bottle and mechanism for driving a staple through the skirt of the hood to secure it around the neck of the bottle, said mechanism comprising means for preshaping a staple with the tips of its tines lying within the radial angle of the curvature of the neck of the bottle as determined by the widest part of the staple, and then driving the staple in that shape through the skirt of the hood for self-clinching against the bottle as an anvil.

5. In a machine for stapling the skirt of a hood around the neck of a bottle, the combination of a support, a staple forming device on the support for shaping a staple with the tips of its tines converging in partially clinched condition, means for driving the staple in that shape into the skirt of the hood for final self-clinching beneath the same against the bottle as an anvil.

6. In a machine for applying a skirted hood to a bottle, the combination of a support for the bottle, means for folding the hood over the mouth of the bottle, and mechanism for driving a staple through the skirt of the hood to secure it around the neck of the bottle; said mechanism comprising means for preshaping the staple with the ends of the tines converging in partially clinched form, parallel guides for the tines of the staple, and means for driving the staple in that form in said guides and through the skirt of the hood for final self-clinching against the bottle as an anvil.

7. In a machine for applying a skirted hood to a container by means of initially partially-clinched wire staples, the combination of a support for the container, means for folding a hood over the container to form a skirt around the container, a plurality of substantially radial guides spaced around said skirt for holding the staples, and means for simultaneously driving

- said staples in said guides through the skirt in said partially-clinched condition before final self-clinching against the underlying container.
8. In a machine for applying a skirted hood to a container by means of initially partially clinched wire staples, the combination of a support for a container, means for folding a hood over the container to form a skirt around it, a plurality of stapling devices spaced substantially radially around said skirt each holding a wire staple, and mechanism for simultaneously projecting said devices into proximity to said skirt and actuating said devices to drive the staples through the skirt while in said partially clinched condition for final self-clinching against the container as an anvil.
9. In a machine for applying a skirted hood to a bottle, the combination of a support for the bottle, means for folding the hood over the mouth of the bottle, the skirt of the hood so folded including a plurality of layers of hood material, means for driving a staple, and means for partially clinching the tines of the staple prior to its application to the hood skirt by said driving means, for penetration of a portion of said layers before final self-clinching upon the underlying layers rendered firm by the support afforded by the bottle.
10. In a machine for applying a skirted hood to a bottle, the combination of a support for the bottle, means for folding the hood over the mouth of the bottle, the skirt of the hood including a plurality of overlapped tabs, means for driving a staple, and means for partially clinching the tines of the staple for penetration of all of the overlapped tabs except the tab next adjacent the bottle neck before final clinching upon said next adjacent tab rendered firm by the support afforded by the underlying surface of the bottle.
11. In a machine for applying a skirted hood to a container, the combination of a support for the container, means for folding the hood over the mouth of the container, said means including devices for upwardly folding the lower edge of the skirt of the hood against the container, mechanism for driving a staple through the skirt of the hood, and means for inwardly deflecting the tines of the staple for self-clinching against the upwardly folded edge of the hood skirt to secure the skirt of the hood around the neck of the container.
12. In a machine for applying a skirted hood to a container, the combination of a support for the container, means for folding the hood over the mouth of the container, the skirt of the hood comprising overlapped portions, means for upwardly folding certain of the portions, and means for driving a staple through the overlapping portions to secure the skirt of the hood around the container.
13. In a machine for applying a skirted hood to a container, the combination of a support for the container, means for folding the hood over the mouth of the container, the skirt of the hood comprising overlapped tabs, and means for upwardly folding the lower edges of certain of said tabs.
14. In a machine for applying a skirted hood to a container, the combination of a support for the container, means for folding the hood over the mouth of the container, the skirt of the hood comprising overlapped substantially radial tabs, means included in the folding means for engaging the lateral edges of certain tabs to lay them straight, and means for securing the tabs together around the container.
15. In a machine for applying a skirted hood to a container, the combination of a support for the container, means for folding the hood over the mouth of the container, the skirt of the hood comprising a plurality of substantially radially extending members, means engaging at least one lateral edge of said members to lay them evenly on the side wall of the container, and means for securing the members around the neck of the container.
16. In a machine for applying a skirted hood to a container, the combination of a plurality of fingers for initially folding the hood over the mouth of the container and for subsequently holding the skirt thereof against the container, and stapling means for stapling the skirt around the container while it is being held by said fingers.
17. In a machine for applying a skirted hood to a container, the combination of a support for the container, the skirt of the hood comprising substantially radial tabs, means for folding alternate tabs in side-by-side relation over the mouth of the container, means for folding the remaining tabs over the adjacent edges of the said alternate tabs, and means for securing the tabs together in this relation around the container.
18. In a machine for applying a skirted hood to a container, the combination of a support for the container, the skirt of the hood comprising substantially radial tabs, means for folding alternate tabs in side-by-side relation over the mouth of the container, means for folding the remaining tabs over the adjacent edges of the said alternate tabs, and means for driving a staple through the said remaining tabs with the tines thereof penetrating the said corresponding alternate tabs.
19. In a machine for applying a skirted hood to a container, the combination of a support for the container, means for positioning a hood over the mouth of the container, a gauge, means for advancing a wire to the gauge and slightly bending the wire to increase its gauged length, means for severing the gauged length of wire, means for forming it into a staple, and means for driving it through the skirt of the hood to secure the latter on the container.
20. In a machine for applying a closure to a container, the combination of a support for the container, a guide for directing a closure over the mouth of the container, means for feeding a strip of connected closures to the guide, means for feeding the strip to the first means with a slack in the strip between the two means, means for severing the leading closure from the strip, and means for applying the severed closure to the container.
21. In a machine for applying a skirted hood to a container, the combination of a support for the container, a guide for a hood blank over the mouth of the container, means for feeding a strip of connected hood blanks intermittently to the guide, means for feeding the hood blank strip intermittently to the first means with a slack in the strip between the means, means for severing the leading hood blank from the strip, and means for folding the hood blank over the mouth of the container.
22. In a machine for applying closures to containers, the combination of a plurality of spaced container holders, a rotating support for said

- holders, a plurality of closure-applying means on said support and aligned with corresponding container holders, a plurality of closure strip reels mounted in superposed relation on and substantially coaxially with said support for rotation therewith, and means for feeding a closure strip from a corresponding reel to each hood-applying means.
23. In a machine for applying a skirted hood to a container by means of initially partially-clinched wire staples, the combination of a support for a container, means for folding a hood over the container to form a skirt around it, a plurality of stapling devices spaced substantially radially around said skirt each holding a wire staple, mechanism for simultaneously positively projecting said devices into proximity to said skirt and actuating said devices to drive the staples through the skirt while in said partially clinched condition for final self-clinching against the surface of the container as an anvil, and means included in said mechanism for compensating for containers of various diameters.
24. In a machine for applying a hood to a container, the combination with a support for the container, a head aligned therewith, means for moving said head and said support relatively to each other to a clamping position, means movable into engagement with said container for centering said container with respect to said head and clamping a hood over the top of the container while in said clamping position, said first means then further moving said support to move said container into said head, means independent of said other means for folding said hood over the container, and means for securing the folded portion of said hood around said container.
25. In a machine for applying a skirted hood to a container, the combination of a support for the container, a head aligned with the support, a plurality of stapling devices for securing the skirt of the hood around the neck of the bottle, a source of power for simultaneously operating the devices, a normally disengaged clutch interposed between the source of power and the devices, means for advancing the support to move

the upper end of the container into cooperative relation with the head, and means responsive to the advancing movement of the container for engaging the clutch.

26. In a machine for applying a skirted hood to a container, the combination of a support for the container, a head aligned with the support, a plurality of stapling devices for securing the skirt of the hood around the container, a source of power for simultaneously operating the devices, a normally disengaged clutch interposed between the source of power and the devices, means for advancing the support to move the upper end of the container into cooperative relation with the head, means responsive to the advancing movement of the container for engaging the clutch, and means interposed between the last named means and the clutch for controlling the operation of the clutch.

27. In a machine for applying a covering to a bottle, the combination of a bottle support, a cover-applying means, said support and means being relatively movable to place the bottle into cooperative relation with the means, centering elements jointly cooperating to embrace the bottle, resilient means normally urging said elements to said closed centering position, mechanism engaging said elements to hold them in retracted position, and means momentarily operative to release said mechanism to permit said elements to embrace and center the bottle.

28. In a mechanism for applying and sealing skirted caps on bottles, the combination of a plurality of cap applying heads, means to rotate said heads about a common axis, means individual to each head to supply a blank of thin sheet material to the corresponding head in position above the mouth of a bottle to be sealed, means for causing relative movement between a bottle and its corresponding head, means associated with each head for folding a portion of the blank into skirt form over the mouth of the bottle, means to seal said cap on the bottle, and means to discharge sealed bottles from said mechanism.
